SLIDE FASTENER

Anthony W. Tripp and Jacob D. Stiriss, New York,
N. Y., assignors to Slidette, Corp., New York,
N. Y.

Application February 8, 1940, Serial No. 317,841

20 Claims. (Cl. 24—207)

This invention relates to slide fasteners, and is particularly directed to slide fasteners wherein a plurality of spaced individual fastener elements are fixed to a flexible strip, and provided with means slidably engaging longitudinal beading on the adjacent margins of a pair of parallel flexible tapes disposed side by side and adapted to be stitched to the edges of a garment, bag or other article at the opening thereof of the type generally disclosed in applicants' co-pending applications Serial Nos. 317,838 and 317,840, filed February 8, 1940.

An object of this invention is to provide in a slide fastener of the character described, individual fastener elements, so constructed as to permit use of a wide variety of buttons or ornaments in the assembly thereof.

Another object of this invention is to provide a slide fastener of the character described, having individual fastener elements adapted to be quickly and easily assembled with the flexible strips.

Yet another object of this invention is to provide in slide fasteners of the character described, a metal fastener element adapted to be attached to a flexible strip by a tack having a head pressing the strip against one side of the fastener element, and a shank passing through an opening in the fastener element, and on which is mounted a button or ornamental member contacting the opposite side of the fastener element, the construction of the fastener element being such that pressure against opposite sides thereof, by the head of the tack and the button or ornament, will not cause the fastener element to clamp the tapes on which it is slidably mounted, whereby the fasteners may be slidably moved on the tapes without binding and without excessive looseness.

Fastener elements of the type generally described herein, were heretofore provided with a pair of longitudinal channels receiving the beads of the tapes, the channels being formed with slots through which the tapes pass. In such construction, the channels contact the beads throughout the entire length of the channels. In order to get friction between the walls of the channels and the beads, the channels had to clamp the beads which caused too great a friction. If the channels did not clamp the bead, the fasteners were too loose on the tapes, and thus it was always difficult to obtain the right amount of friction. It is therefore a further object of this invention to provide a construction of the character described, in which the friction

on the bead is not either too loose or too tight.

In prior constructions, furthermore, when the channel walls were of uniform cross-section throughout, if the ends of the slotted walls through which the web portions of the tapes passed, were not rounded at the ends, there would be a tendency to cut the beads. If the ends of the slotted walls were curved, the beads would have a tendency to wedge into the slots between the rounded ends of the slotted walls and prevent the fastener element from properly sliding on the tapes. It is therefore yet another object of this invention to overcome this difficulty by providing a construction in which the bead cannot be cut or wedged, and in which the friction on the bead is between rounded surfaces and straight surfaces at the mid portions of the fasteners.

A still further object of this invention is to provide in a slide fastener of the character described, fastener elements which are so shaped as to permit use of smaller or round buttons or ornaments without showing the element, and in which the elements will contact when the slide fastener is drawn to open position, instead of the buttons or ornaments contacting.

Still another object of this invention is to provide slide fasteners of the character described, in which the flexible strip with the fastener elements thereon may be readily removed from or attached to the strips of tape.

Yet another object of this invention is to provide a strong and durable slide fastener of the character described, which shall be relatively inexpensive to manufacture, easy to manipulate, attractive in appearance, and yet practical and efficient to a high degree in use.

Other objects of this invention will in part be obvious and in part hereinafter pointed out.

The invention accordingly consists in the features of construction, combinations of elements, and arrangement of parts, which will be exemplified in the construction hereinafter described, and of which the scope of application will be indicated in the following claims.

In the accompanying drawings, in which are shown various possible illustrative embodiments of this invention,

Fig. 1 is a front elevational view of slide fastener construction, embodying the invention;

Fig. 2 is a rear elevational view of the structure shown in Fig. 1, with parts broken away and in cross-section;

Fig. 3 is a cross-sectional view taken on line 55 3—3 of Fig. 1;

Fig. 4 is a cross-sectional view taken on line 4—4 of Fig. 3;

Fig. 5 is a cross-sectional view taken on line 5—5 of Fig. 3;

Fig. 6 is a cross-sectional view taken on line 6—6 of Fig. 3;

Fig. 7 is a cross-sectional view taken on line 7—7 of Fig. 4;

Fig. 8 is a perspective view of two parts of the fastener element separated from each other;

Fig. 9 is a view similar to Fig. 5, but illustrating a modified construction;

Fig. 10 is a view similar to Fig. 9, but illustrating a still further modified construction;

Fig. 11 is a bottom plan view of the leader ends of the tapes;

Fig. 12 is a front elevational view of the handle for the uppermost button, illustrating a modified construction;

Fig. 13 is a cross-sectional view taken on line 13—13 of Fig. 12.

Fig. 14 is a cross-sectional view similar to Fig. 9, but illustrating a modified construction for fastening the ornamental button and tape to the slider;

Fig. 15 is a view similar to Fig. 14, but illustrating a further modified construction; and

Fig. 16 is a view similar to Fig. 15, and illustrating another modified construction.

Referring now in detail to the drawings, 10 designates a slide fastener construction embodying the invention, comprising a pair of symmetrically disposed, spaced, elongated, parallel strips of tape 12. Each tape 12 has an elongated bead 13 at one edge, and a web portion 13a extending from the bead. The beads 13 of the tapes 12 are spaced from and adjacent to one another, and the web portions 13a are in a common plane. The tapes 12 are stitched, as at 14, to longitudinal, spaced, edge portions 15 at the opening of a garment, bag or other article, with the beaded portions of said tapes projecting inwardly beyond said edge portions 15.

Means is provided for fastening together the tapes 12 longitudinally. To this end, there is provided an elongated, flexible strip 16 of cloth or any other suitable material, and attached to said strip 16, are a plurality of spaced fastener members 17. Each fastener member 17 comprises a fastener or slider element 18, preferably made of metal, attached to the strip 16 by means of a tack 19 and button or ornamental member 20, in the manner hereinafter appearing.

Each fastener element 18 is made of two similar, symmetrically disposed parts 23. Each part 23 has a wall 24 provided with a pair of similar, parallel, longitudinal side flanges 25. Each wall 24 is formed with a central recessed, annular, cupped portion 27, formed with a central opening 28. The height of each recessed portion 27 is somewhat greater than the width of the flanges 25, whereby said recessed portion extends beyond said flanges. At one end of the wall 24, is a curved portion 30 formed with a dove-tailed central slot 31. Extending from the other end of the wall 24, is a central curved portion 33, from which there extends at right angles to said wall, a tab 34 having at its outer end a double pointed prong 35, and a pair of shoulders 36 on opposite sides of said prong. The length of the prong 35 from the wall 24 to the shoulder 36, is preferably twice the height of each recessed portion 27.

The parts 23 are assembled together by snapping the prongs 35 of each part into the dove-tailed slot 31 of the other part, so that the shoul-

ders 36 of each part contact the underside of the wall portion 30 of the other part. The prongs 35 are then riveted outwardly, to fix the two parts together. The bottoms of the recessed portions 27 will also contact one another so that the openings 28 register. When the parts 23 are assembled, a slot 38 will be formed between each pair of flanges 25 to receive the webs 13a of tapes 12. Channels 38a are also formed between portions 27 and flanges 25 to receive the beads 13 of said tapes.

The beads 13 are received between the annular portions 27 and the flanges 25 of the elements, and the webs 13a of the tapes 12 pass through the slots 38. The beads 13 are somewhat clamped between the rounded portions 27 and the mid portions of the straight flanges 25, to produce sufficient friction to hold the fastener elements at any position to which they are slidably moved on the beads.

It will be noted that the end openings 13b of the channels 38a, on each side of the tabs 34, through which the beads 13 pass, are sufficiently wide to permit the beads to loosely pass therethrough without any clamping action, so that the only clamping action between the fastener elements and the beads, is between the annular portions 27 and the mid-portions of the straight flanges 25.

Each tack 19 has a head 19a and a screw threaded shank 19b. The strip 16 contacts the outer surface of one of the walls 24 of each fastener element and extends longitudinally thereof. The threaded stem or shank of the tack 19 pierces the strip and passes through the registering openings 28.

Each button 20 preferably has a central recessed opening 40 on one surface thereof, and pressed into said recess, is the conical end 41 of an element 42. Said element 42 has a tubular, axial internally screw threaded portion 43 passing through the openings 28 of the fastener element 18, and receiving the screw threaded stem 19b of the tack 19.

It will be noted that the conical portion 41 is spread outwardly and pressed into the recess 40 of the button 20, so that the element 42 will become firmly fastened to said button. The button may then be readily screwed to the shank of the tack 19.

It will now be understood that the buttons may be quickly assembled with the tacks 19 and elements 18, and the buttons may be readily replaced so that a wide variety of buttons or ornamental members may be employed. It will be noted that when the tack is screwed tight to the button, the pressure is taken up by the tabs 34, as well as the central cup-shaped or recessed portion 27, and pressure will not cause the flanges 25 to clamp against the web portions 13a of the tape. The width of the slots 38 is thus maintained constant.

In prior constructions, the beads in fastener elements of the general type described herein, were received in longitudinal channels frictionally engaging the beads throughout the length of the channel, and with such construction, the friction on the bead was either too great or too little making the fasteners either too tight or too loose. In the present construction, since the pressure on the bead is between an annular or rounded surface and a flat or straight surface, a proper amount of friction may be obtained so that the fastener elements will easily slide on the tapes 12 and will be set in any position to which

they are moved. Since the openings at the ends of the fasteners loosely receive the beads, there is no cutting of the beads, thus adding to the life of the fastener construction.

It will be noted that the corners 25a of the flanges 25 are balled, that is, they are square edges, but not sharp. This construction prevents the tape from wedging in between the flanges, as there is not sufficient curvature to give the beads the start to wedge in between the flanges 25.

It will be noted that the corners of the walls 24 are cut away, and with this construction, the fastener elements 18 will contact when the fasteners are pushed together to open up the garment or bag. Nevertheless, the buttons 20 will cover the entire walls 24. The necessary length of the fastener elements is thus maintained without showing the corners of the elements when using round buttons, thus permitting the use of smaller buttons or round buttons without showing the elements 18.

Fixed to the lower ends of the tapes 12 are metal leaders 50, having web portions 51 aligned with the web portions 13a, and tapered beaded portions 52 aligned with the beads 13. The leaders may be easily threaded through the fastener elements 18, so that the entire strip 16 with its fasteners 17 may be readily removed, as when the garment is being laundered or cleaned.

The tapered beaded split tubular portions 52 of the leaders compress the beads 13 of the tapes 12 so as to be of such size that they may readily pass through the channels 38a of the fastener elements. The web portions 51 of each leader 50 extends from the tapered tubular portion 52 thereof, contacting opposite sides of the web 13a of the tape 12, and are riveted together by an eyelet 54b. The tubular portions 52 extend above the web portions 51, and the lower end edges 13c of the web portions 13a of the tapes are inclined downwardly and outwardly, the inner ends of said inclined edges terminating at the upper ends of the web portions of the leaders, so that the web portions of the leaders may be pressed together into contact below the end edges of the tapes so as to be sufficiently thin, adjacent the tubular portions 52, to pass through the slots 38 in the fastener elements.

The uppermost member 17 may be provided with a transverse bar 54, to which is attached a handle 55, for pulling the fasteners downwardly to open up the garment, or upwardly, to close the opening in the garment. The transverse bar 54 has a central portion 56 eyeleted to the element 18, and passing through the openings 28. The handle 55 may be pivoted to the cross-bar 54 in any suitable manner.

In Fig. 9 the threaded shank 19b of the tack 19, is driven directly into a composition button 60.

In Fig. 10 the threaded stem 19b of the tack 19, is screwed to a threaded tubular portion 62 of a member 63 having a ring portion 64 to receive an ornamental device 66.

In Figs. 12 and 13 there is shown a modified form of handle for the uppermost fastener. Riveted to the uppermost fastener element is a cross-bar 54a similar to the cross-bar 54, with the exception that the outer ends are punched into hemi-spherical shape, as shown at 70 in Fig. 13. Attached to the hemi-spherical portion 70, at the ends of the cross-bar 54a are socketed members 72. Each socketed member 72 has an upper socket 73 to receive the portions 70, and lower socketed member 74. The portions 74 grip the outer ends of a flexible connector 75,

which may serve as a handle, or to which there may be attached a tab 76 serving as a handle to pull down the fasteners.

It will be noted that the members 72 are connected to the cross-bar by a ball and socket connection, thus facilitating movement of the handle without twisting the cross-bar.

In Figs. 14, 15 and 16 there is shown sliders embodying the invention, and illustrating modified forms thereof. In each case, the slider element 18 is the same as shown in Fig. 8 of the drawings.

In Fig. 14, however, an ornamental member or button 80 has fixed thereto a stem 81 projecting through the registering openings 28 and frictionally received in a tubular rivet 83, having a head 84 partially received within the central recess of one of the parts 23, and pressing a portion of the tape 16 into said recess. Thus, the head 84 of the rivet 83 is smaller, so as to press a portion of the tape into the recess, thus firmly gripping the tape.

In Fig. 15 the button 80 is attached to the slider 18 by means of a riveted eyelet 95 having a head 96 pressing a portion of tape 16 into the recessed portion 27 of one of the slider parts 23.

In Fig. 16 there is attached to the button 80, a tubular stem 97 receiving the stem 98 of a fastener having a head 99 which presses the central portion of the tape 16 into the recessed portion 27 of slider element part 23.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described our invention, we claim as new and desire to secure by Letters Patent:

1. In a slide fastener, a flexible strip, and a plurality of spaced fastener elements fixed to each strip, each element having means to slidably engage said beading on a pair of parallel pieces of tape, and an ornamental member mounted on each fastener element.

2. A slide fastener comprising an elongated flexible member, a plurality of spaced fastener elements contacting said flexible member, means for attaching said tape to one side of each fastener element, each element having means for slidably engage the beading on a pair of pieces of tape, and an ornamental member attached to the other side of each fastener element.

3. A slide fastener comprising an elongated flexible member, a plurality of slider elements having means to slidably engage beading on a pair of parallel flexible tapes, each element having an opening, means extending through said openings to attach said flexible member to said elements, said element being disposed on one side of said flexible member, and an ornamental member attached to the other side of each element.

4. A slide fastener comprising an elongated flexible strip adapted to extend longitudinally of a pair of parallel pieces of tape having marginal beading, a fastener element contacting one side of said strip, and provided with means slidably engaging said beading, and being formed with an opening, a member having a head contacting the other side of said strip, and a shank

passing through said strip and through said opening, and a member gripping said shank to fasten said member and element to said strip.

5. In a slide fastener, a flexible strip, a plurality of spaced fastener elements on said strip, each element being formed with a pair of spaced parallel slots, and with a through opening between said slots, a member having a shank passing through the strip and the opening of each element, each member having a head, the strip being interposed between said elements and the heads of said members, and ornamental members overlying said elements and gripping the shanks of said members.

6. A fastener element having parallel, spaced walls, each wall having a pair of parallel flanges extending toward the other wall, the flanges of each side of said element being aligned with one another, and the inner edges thereof being spaced from one another to form a slot, and means disposed between the flanges of each wall and spaced inwardly thereof, interconnecting said walls and spacing said walls from one another.

7. A fastener element having parallel, spaced walls, each wall having a pair of parallel flanges extending toward the other wall, the flanges of each side of said element being aligned with one another, and the inner edges thereof being spaced from one another to form a slot, and means disposed between the flanges of each wall interconnecting said walls and spacing said walls from one another, said walls each being formed with a central recessed portion, the bottoms of said recessed portions contacting one another and formed with central registering openings.

8. A fastener element adapted to slidably receive the longitudinal beads of a pair of flexible tapes, said element being made of two similar, symmetrically disposed, metal parts, each part having a wall formed with a pair of parallel longitudinal flanges at its sides, the flanges of one part being aligned with and spaced from the flanges of the other part to form longitudinal slots between said flanges at the sides of the fastener, each part being formed with a portion extending from said wall thereof, bent over the wall of the other part to prevent separation of said parts, and having a shoulder engaging said wall of said other part, to space said parts, whereby said walls are held in spaced, parallel relation to one another.

9. A fastener element adapted to slidably receive the longitudinal beads of a pair of flexible tapes, said element being made of two similar, symmetrically disposed, metal parts, each part having a wall formed with a pair of parallel longitudinal flanges at its sides, the flanges of one part being aligned with and spaced from the flanges of the other part to form longitudinal slots between said flanges at the sides of the fastener, each part being formed with a portion extending from said wall thereof, riveted to the wall of the other part and having a shoulder engaging said wall of said other part, whereby said walls are held in spaced, parallel relation to one another, said walls being formed with registering openings, a flexible strip contacting one of said walls, a member having a shank piercing said strip and passing through said registering openings and having a head contacting said strip to press the same against said wall, and a button fastened to said shank.

10. A fastener element having spaced parallel walls, and said walls each having parallel flanges, the flanges of one wall being aligned with and

spaced from the flanges of the other wall, means interconnecting said walls, located between the planes of said flanges, a flexible strip attached to one side of said element, and an ornamental member on the other side of said element.

11. A fastener element having spaced parallel walls, and said walls each having parallel flanges, the flanges of one wall being aligned with and spaced from the flanges of the other wall, means interconnecting said walls, said means being located between the planes of said flanges, and said walls being formed with registering openings, a flexible strip contacting the outer surface of one of said walls, a member contacting the other of said walls, and means extending through said openings to fix said strip and member to said element.

12. In a slide fastener made of two similar, symmetrically disposed metal parts, each part having a flat wall provided with parallel side flanges extending at right angles to said wall, a tab at one end of said wall disposed perpendicularly to said flanges and wall, prongs at the ends of said tab, said tabs each being formed with shoulders adjacent said prongs, and said wall having a groove at the opposite end thereof, the prongs on the tab of each part being received within the groove of the other part, and the shoulders of said tab contacting said wall of said other part, and said prongs being riveted over said other part for attaching said parts together, the flanges of one part being aligned with the flanges of the other part, and spaced therefrom, whereby to form a longitudinal slot on each side of the fastener.

13. In a slide fastener made of two similar, symmetrically disposed metal parts, each part having a flat wall provided with parallel side flanges extending at right angles to said wall, a tab at one end of said wall disposed perpendicularly to said flanges and wall, prongs at the ends of said tab, said tabs each being formed with shoulders adjacent said prongs, and said wall having a groove at the opposite end thereof, the prongs on the tab of each part being received within the groove of the other part, and the shoulders of said tab contacting said wall of said other part, and said prongs being riveted over said other part for attaching said parts together, the flanges of one part being aligned with the flanges of the other part, and spaced therefrom, whereby to form a longitudinal slot on each side of the fastener, said wall of each part being formed with a central recessed apertured portion disposed between the side flanges of said part, and the inner ends of said recessed apertured portions contacting one another and the openings therein registering with one another.

14. In a slide fastener made of two similar, symmetrically disposed metal parts, each part having a flat wall provided with parallel side flanges extending at right angles to said wall, a tab at one end of said wall disposed perpendicularly to said flanges and wall, prongs at the ends of said tab, said tabs each being formed with shoulders adjacent said prongs, and said wall having a groove at the opposite end thereof, the prongs on the tab of each part being received within the groove of the other part, and the shoulders of said tab contacting said wall of said other part, and said prongs being riveted over said other part for attaching said parts together, the flanges of one part being aligned with the flanges of the other part, and spaced there-

from, whereby to form a longitudinal slot on each side of the fastener, said wall of each part being formed with a central recessed apertured portion disposed between the side flanges of said part, and the inner ends of said recessed apertured portions contacting one another and the openings therein registering with one another, a strip of tape contacting the outer surface of the wall of one of said parts, a member contacting the wall of the other of said parts, and means extending through said openings to attach said strip and member to said element.

15. A fastener element having spaced parallel walls, and said walls each having parallel flanges, the flanges of one wall being aligned with and spaced from the flanges of the other wall, means interconnecting said walls, said means being located between the planes of said flanges, and said walls being formed with registering openings, a flexible strip contacting one of said walls, a tack having a screw threaded shank piercing said strip and passing through said openings, a button having a recess in one surface thereof, a member having an outwardly flared portion, and a tubular, internally screw threaded portion extending from said flaring portion, said flaring portion being force fitted into said recess, and said shank being screwed into said tubular portion.

16. A fastener element having parallel spaced walls, each wall having a pair of parallel flanges extending toward the other wall, said walls each being formed with a central recessed portion contacting one another and forming a means to frictionally engage the bead of the tape in the mid-section of the fastener element.

17. In combination, a fastener element, a piece of tape attached thereto, a cross-bar fixed immediately the ends thereof to said fastener element, a pair of members having ball and socket connection with the outer ends of said cross-bar, and a flexible element interconnecting said pair of members.

18. In combination, a pair of similar, symmetrically disposed, spaced tapes having longitudinal beads at their inner edges, and web portions extending from said beads, a plurality of

fastener elements slidably mounted on said beads and having slots receiving the web portions of said tapes, a strip attached to said fastener element, and a pair of leaders at the lower ends 5 of said tapes, said leaders being made of metal and having tubular portions receiving the beads of said tapes, and web portions receiving the web portions of the tapes, said tubular portions extending above the web portions of said leaders, and part of the web portions of said tapes terminating above the lower ends of the web portions of said leaders, adjacent the tubular portions thereof, whereby opposite walls of said leader contact where the wet portion of the tape is removed.

19. A slider element comprising a pair of metal parts, means on said parts for attaching said parts together, said slider having spaced parallel walls, each wall having a pair of parallel flanges, the flanges on one wall being aligned with and extending toward the flanges on the other wall, the adjacent edges of said flanges being spaced to form slots, one of said walls being formed with a recess, a strip of tape contacting said wall, and means for attaching said strip of tape to said wall, including a fastening member having a portion disposed within the recess and pressing a portion of said strip of tape into said recess.

20. A slider element comprising a pair of metal parts, means on said parts for attaching said parts together, said slider having spaced parallel walls, each wall having a pair of parallel flanges, the flanges on one wall being aligned with and extending toward the flanges on the other wall, the adjacent edges of said flanges being spaced to form slots, one of said walls being formed with a recess, a strip of tape contacting said wall, means for attaching said strip of tape to said wall, including a fastening member having a portion disposed within the recess and pressing a portion of said strip of tape into said recess, and an ornamental member attached to said slider and contacting the other wall thereof.

ANTHONY W. TRIPP.
JACOB D. STIRISS.
